UNITED STATES PATENT OFFICE.

JOSEPH CHALUPSKY, OF WEED, CALIFORNIA.

DESIGN FOR A HAT-PIN GUARD.

47,027.

Specification for Design.

Patented Mar. 2, 1915.

Application filed December 2, 1914. Serial No. 875,169. Term of patent 3½ years.

To all whom it may concern:

Be it known that I, JOSEPH CHALUPSKY, a subject of the Emperor of Austria-Hungary, residing at Weed, in the county of Siskiyou and State of California, have invented a new, original, and ornamental Design for a Hat-Pin Guard, of which the following is a specification, reference being had to the accompanying drawing, forming part thereof.

Figure 1 is an elevation of my hat-pin guard, showing my new design, and Fig. 2 is a plan view of same.

I claim:

The ornamental design for a hat-pin guard, as shown.

JOSEPH CHALUPSKY.
